UNITED STATES PATENT OFFICE.

PINCUS BURGER, OF BROOKLYN, NEW YORK.

DESIGN FOR A CEILING FIXTURE.

Application filed February 28, 1929. Serial No. 30,249. Term of patent 3½ years.

To all whom it may concern:

Be it known that I, PINCUS BURGER, of Brooklyn, county of Kings and State of New York, have invented a new, original, and ornamental Design for a Ceiling Fixture, of which the following is a specification, reference being had to the accompanying drawing, forming a part hereof.

In the drawing:

Figure 1 is an inverted plan view of the ceiling fixture, part in elevation, the parts shown in full line outline being ornamented in the same manner as the parts more fully illustrated; and

Figure 2 is a diagrammatic side elevational view of the same.

I claim:

The ornamental design for a ceiling fixture, substantially as shown and described.

PINCUS BURGER.
